UNITED STATES PATENT OFFICE.

MOSES A. JOHNSON, OF LOWELL, MASSACHUSETTS.

IMPROVEMENT IN COVERINGS FOR STEAM-BOILERS.

Specification forming part of Letters Patent No. 37,967, dated March 21, 1863.

To all whom it may concern:

Be it known that I, MOSES A. JOHNSON, of Lowell, in the county of Middlesex and State of Massachusetts, have invented a new and useful Improvement in Felt for Covering Boilers, Steam-Pipes, and other similar uses; and I do hereby declare that the following is a full, clear, and exact description of the same.

This invention consists in impregnating and coating felt, whether made of hair or other material, with silicate of soda or soluble glass, the object being to prevent its being charred by the heat of a boiler or other apparatus to which it may be applied, and renders it a better non-conductor of heat and protection against combustion, thereby enabling a felt of less thickness to be used than would otherwise be required.

For impregnating the felt I use the silicate solution in a weak form and rub it in by the action of a filter; but for coating it I employ a strong solution, which may be applied with a brush or by other means, like a varnish, to one or both sides, particularly to the side which

is to be applied next the boiler or other heated surface. The surfaces may be afterward washed with a solution of chloride of calcium to prevent efflorescence from the action of the atmosphere, if under any conditions that may be found necessary.

For some purposes it may be necessary only to impregnate the felt, and for others only to coat it with the solution; but generally it may with advantage be both impregnated and coated.

Other incombustible and non-conducting substances—soapstone-dust, for instance—may be mixed with the silicate-of-soda solution.

What I claim as my invention, and desire to secure by Letters Patent, is—

The impregnation and coating of felt with silicate of soda, substantially as and for the purpose herein specified.

MOSES A. JOHNSON.
